UNITED STATES PATENT OFFICE.

THOMAS F. LEAHEY, OF POUGHKEEPSIE, NEW YORK.

PANTS-PRESS.

1,112,922.

Specification of Letters Patent.

Patented Oct. 6, 1914.

Application filed September 4, 1913. Serial No. 788,130.

To all whom it may concern:

Be it known that I, THOMAS F. LEAHEY, a citizen of the United States, residing at Poughkeepsie, in the county of Dutchess and State of New York, have invented certain new and useful Improvements in Pants-Presses, of which the following is a specification.

- This invention relates to a pants presser.
- 10 The primary object of this invention is to provide an article of this character made in one single piece of cardboard or other similar material comprising a body portion and lateral inwardly foldable side members 15 or flaps, and so constructed or designed that it may be doubled up or folded together in such a way that it may be conveniently carried in a suit-case or trunk either with the pants in position or not.
- 20 The device is so designed that when the side members or flaps are folded in, it is of approximately the same shape or configuration as a pair of pants when laid out lengthwise and is adapted to receive the pants 25 under such conditions for the purpose of pressing and creasing the same as above indicated. It may also be doubled or folded together lengthwise one or more times in addition to the folding in of the side members 30 or flaps to render it more compact for convenience in carrying or packing in a suit-case or trunk, it being understood that the pants may be in position or not under such circumstances.
- 35 With the foregoing objects in view, the invention consists in the novel features of construction illustrated in the drawings and more particularly pointed out in the appended claims.
- 40 In the accompanying drawings:—Figure 1 is a plan view showing the device opened out to receive a pair of pants. Fig. 2 is an elevation showing how the side members are folded in and clamped together during the 45 operation of pressing a pair of pants. Fig. 3 is a similar view showing how the device may be doubled up for convenience in carrying or packing. Fig. 4 is an edge view of Fig. 3 and Fig. 5 is an end view of Fig. 2.
- 50 Referring to the drawings for a more particular description of the invention, the device comprises the body portion 1 which is of gradually tapered form and the inwardly folding side members 2 and 3, respectively.
- 55 The presser is made of one piece of fiber board or other suitable material, the side
- members 2 and 3 being integral with the body portion 1 and adapted to fold inwardly along the dotted lines 4 and 5, respectively. The side members are formed 60 with the inwardly inclined outer edges 6 which are disposed flush with the side edges of the body portion 1 when the side members are folded in. Attention is also called to the fact that the side members 2 and 3 are slit at 7, that is, are divided in half 65 sections so that the complete device may be doubled up on the dotted line 8 of the body portion 1, for convenience in packing or carrying in a suit-case or trunk, as shown in 70 Fig. 3.
- The side member 3 of the device is provided at its outer edge with the connecting clamps or clips 9 which are slidably secured or engaged with the outer edge of said side 75 piece by the rivets or buttons 10 co-operating with and having a slidably engagement with the straight longitudinally slotted portions 11 of the clamps or clips. The outer or free 80 ends of the clips are provided with the inwardly curved or bent portions 12 adapted to hook over or engage the outer edge of the outer face of the body portion 1 of the device, as shown in Fig. 5, whereby the side members are clamped or held in inwardly 85 folded position, as a result of which the pants are held in the presser under the requisite pressure to obtain good results.
- From the foregoing description taken in connection with the drawings, it is thought 90 that the construction and operation of this invention will be readily understood without requiring a more extended explanation.
- Various changes in the form, proportions and minor details of construction will be resorted to without departing from the principles or sacrificing any of the advantages of this invention as defined in the appended claims.
- Having described my invention what I 100 claim as new, is:—
1. A device of the character specified comprising a body portion and inwardly folding side members with means for securing or holding the side members in folded position, 105 said means consisting of clamps or clips slidably engaged with the outer edge of one side member and adapted to hook over or engage one edge of the body portion of the device, when the side members are folded in.
  2. A device of the character specified comprising a body portion and inwardly folding

side members with means for securing or holding the side members in folded position, said means consisting of clamps or clips slidably engaged with the outer edge of one side member and adapted to hook over or engage one edge of the body portion of the device, when the side members are folded in, the side members being slit or divided in half sections whereby the device, as a whole, may 10 be doubled up for convenience in packing and carrying.

3. A device of the character specified comprising a body portion and inwardly folding side members with means for securing or holding the side members in folded position, said means consisting of clamps or clips slidably engaged with the outer edge of one side member and adapted to hook over or engage one edge of the body portion of the 20 device when the side members are folded in, said clips or clamps having straight inner longitudinally slotted portions and inwardly curved or bent portions.

4. As an article of manufacture, a pants presser formed from a single blank or strip 25 of fiber board and comprising a main or body portion and inwardly folding side members or flaps and means for securing or clamping the parts in folded position, said means consisting of transversely disposed 30 clips or clamps engaged with the outer edge of one side member and adapted to hook over or engage one edge of the body portion of the device.

35 5. As an article of manufacture, a pants presser formed from a single blank of fiber-board and comprising the following parts:

a body portion having convergent or inclined side margins and adapted to be folded transversely upon itself, an inwardly folding flap member on each of the opposite sides of the body portion, the first of said flap members being adapted to be folded against the body and the second to be folded over upon the first, and both flap members 45 being slit or divided at the folding line of the body portion, whereby the flaps may be first folded inwardly and the device with the pants in it may be folded together in 50 compact form.

6. As an article of manufacture, a pants presser formed of a single blank of fiber-board and comprising the following parts: a body portion adapted to be folded transversely upon itself, an inwardly folding flap member on each of the opposite sides of the body portion, the first of said flap members being adapted to be folded against the body and the second to be folded over upon the first to hold the latter in its folded relation, and both flap members being slit or divided at the folding line of the body portion, in combination with means for securing the flap members in folded relation, comprising a series of clip members having inwardly curved portions adapted to be pressed over the edges of the folded fiber-board.

In testimony whereof I affix my signature in presence of two witnesses.

THOMAS F. LEAHEY.
